ALPHONSE GABRIEL, OF OAKLAND, CALIFORNIA

COIN CONTROLLED LOCK

Application filed May 3, 1927. Serial No. 188,472.

My invention relates to a door-lock which is arranged to be rendered operable by and upon the deposit of a coin, or the like, therein, and particularly relates to improvements in 5 a lock of the type disclosed in my application Serial No. 115,223 filed June 11, 1926.

An object of the invention is to provide a lock of the class described having a single means operated by the lock to prevent the 10 insertion of a second coin while a first coin is operatively disposed in the lock and to positively indicate the presence of the first coin in the lock.

Another object of the invention is to provide 15 a coin-controlled lock with means positively insuring the ejection of an operating coin from the lock mechanism when an exit operation of the lock is effected.

A further object of the invention is to provide 20 in a lock of the class described, an improved closure means for the coin receptacle of the lock.

The invention possesses other objects and 25 features of advantage, some of which, with the foregoing will be set forth in the following description of the preferred form of the invention which is illustrated in the drawings accompanying and forming part of the specification. It is to be understood, however, 30 that variations in the showing made by the said drawings and description may be adopted within the scope of the invention as set forth in the claims.

Referring to said drawings: 35 Figure 1 is a side sectional view of a lock embodying my invention.

Figure 2 is a side view of the lock, portions thereof being broken away.

Figure 3 is an edge view of the lock 40 installed on a door, portions of the lock structure being broken away.

Figure 4 is a fragmentary front view of the lock.

Figure 5 is a view similar to Figure 4 of 45 a modified form of the lock.

Figure 6 is a section taken at the line 6—6 in Figure 1.

As illustrated in the drawings, the lock 7 of my invention comprises a movable latch plate 8 carrying a latch bolt 9, and means

independently operable from different sides of the door for actuating the latch-plate to withdraw the bolt, one of said means being coin-controlled. The lock mechanism, it will be noted, is here shown mounted on a plate 55 11 arranged to be secured directly to a door 12, which plate conveniently serves as a part of the lock housing. Movement of the latch-plate is arranged to be accomplished from the outer side of the door upon the appropriate manipulation of a spindle 13 which carries a member 14 having an arm 16 extending radially therefrom, which latter, in cooperation with a coin, is directly utilized 60 in effecting the movement of the latch plate. 65

The latch-plate 8, it will now be noted, is mounted for reciprocation above the spindle 13 in suitable guideways provided in the plate 11 and a plate 17, which latter plate is arranged to be held in fixed opposed relation 70 to the plate 11 by means of cooperating spacing posts 18 extending from the plate, and screws 19. Furthermore, the latch plate is vertically slotted at its inner end to provide a space 21 in which the arm 16 is arranged to be 75 normally permitted to freely oscillate without effecting any movement of the latch-plate. The latch-plate portions 22 which provide the side walls of the space 21 are provided with opposed vertically disposed grooves 23 of 80 such depth that together they define a guideway for a coin of the denomination to be used in the lock. When, as shown in Figure 1, a coin 24 is disposed in the slots 23, it will be

obvious that the rotation of the arm 16 from 85 a position forwardly of the coin will cause it to engage the latter, and that further rotation of the arm will cause the retractive movement of the latch-plate through the engagement of opposite portions of the coin against the 90 rearward edges of slots 23. In this manner, the coin itself is actually utilized as an operative part of the lock, since without it the retraction of the latch-plate by means of arm 16 is impossible. The arm 16, it will be noted, 95 is arranged to be normally held positioned forwardly of the coin slots 23 by means of a suitable spring 27 operatively connecting the member 14 to a point on the plate 11 forwardly of said member, the forward move- 100

ment of the arm being limited by its contact with the forward wall 28 defining the space 21, so that the arm 16 will thus normally lie in fixed relation to the latch-plate.

5 Means are provided for holding the coin in proper operative position in the slots 23 during the oscillation of the arm, and, as here shown, such means comprise the provision of a shoulder or seat 29 at the base of the arm 16 so disposed that the lower edge of the coin will rest and be held thereon when the coin is properly positioned in the slots. In this manner, movement of the arm toward the coin will not dislodge the latter until the latch-plate has been retracted and operation of the latch in the manner specified is assured.

In locks of the class described it is usually desirable to be able to open the door from the inner side independently of the coin controlled means, and, as here shown, means are provided comprising a second spindle 31 having a radial arm 32 extending therefrom to engage the rearward wall 33 of the space 21 and operable from the inside of the door to thus retract the latch-plate independently of the arm 16. The slots 23, it will now be noted, are somewhat wider than the thickness of the coin and the seat 29 slopes rearwardly and downwardly, so that when the arm 16 retracts the latch-plate to its rearward position the coin will slide downwardly from its seat and out of the slots. In this manner, the placing of a coin in the lock mechanism will allow the retraction of the bolt by the operation of the spindle 13 from the outside of the door, while the operation of the spindle 31 to cause the retraction of the latch-plate will open the door from the inner side thereof.

To insure the release of a coin from the mechanism upon the operation of the spindle 13, a leaf spring 34 is provided, such spring being disposed to engage and slidably bear upon the top of the coin when the latch bolt is withdrawn, so that should the coin tend to remain in the lock when spindle 13 is operated, its engagement with spring 34 will force it from its seat.

Means are provided for barring the insertion of a coin or other object in the latch plate and behind the arm 16 when the latter is positioned rearwardly of the plane of the guideway as by the turning of the spindle with or without a coin operatively disposed in the lock. As here shown, such means comprises a projection 37 extending forwardly from the end of the arm generally at right angles thereto and arranged to extend across and over the upper end of the space defined by slots 23 when the arm is in the position stated. In this manner, in the event that the spindle 13 is rotated prior to the insertion of a coin in the guideway, the deliberate or accidental holding of the latch-plate in withdrawn position by the insertion of such coin or other foreign object in the latch-plate

is positively prevented, it being noted that the projection 37 is preferably so positioned and of such width as to substantially completely cover the portion of the latch plate opening 21 forwardly of the arm 16 when the arm is in its rearward position. In this manner, a coin or other object inserted while the arm 16 is retracted will merely ride on the top of the projection 37 thereof and so be kept out of the operative mechanism.

Insertion of the coin into the slots 23 is arranged to be effected from the front of the lock, and the plate 17 is accordingly provided with a vertically directed slot 38 generally opposite the upper side of the latch-plate, which slot is preferably no longer than the diameter of a coin of proper size. Preferably, and as here shown, the slot 38 extends slightly below the top line of the latch plate 8, and a portion of the adjacent latch-plate wall 22 at the upper end of its groove 23 is cut away as at 40. In this manner, the latch plate itself bars the insertion of a coin of proper size for use in the lock except when the grooves 23 and slot 38 are in coplanar relation.

Means are provided for effecting a closure of the slot 38 following the operation of the lock by means of spindle 13 and prior to the release of the coin from the mechanism. Slidably mounted on the outer side of the plate 17 for reciprocative movement in the same direction as that of the latch plate is a plate member 39, such member being here shown slidably secured to the plate 17 by means of headed posts 41 engaged in slots 42 of the plate 39 and screwed to the plate 17. The plate 39, it will be noted, is resiliently urged to be disposed in its forward, or inoperative position, by suitable means such as the flat coil spring 43 here shown mounted on the plate 17 by means of one of the screws 19 and having the free end thereof operatively bearing against the rear edge of the plate 39. A rearwardly directed edge 44 is provided on the plate 39, such edge being arranged to be normally disposed adjacent the forward edge of the slot 38 to extend vertically therewith whereby the slot will be left open when the plate 39 is in its forward position and will be covered when the plate is moved rearwardly.

It will now be noted that an outwardly extending pin 46 is provided on the outer side of the latch plate, such pin extending through a slot 47 provided in the portion of plate 17 opposite thereto and into the plane of the plate 39. A forwardly directed edge portion 48 is provided on the plate 39 for engagement with the pin 46 whereby retraction of the latch plate 8 will effect the retraction of the plate 39. It will now be clear that when the lock bolt is withdrawn by the aid of the coin, the operative positioning of plate 39 to effect a closure of the slot 38 will be

simultaneously effected, but that if the plate 39 is at all times freely movable with the latch plate, the slot 38 would be opened again when the bolt returns to its operative 5 position. Means are accordingly provided for securing the plate 39 in operative position after its disposal in such position by means of the operation of the lock through the coin, such means being arranged for the 10 release of the plate only when the exit, or inside, spindle 31 is operatively rotated.

Mounted on the plate 17 adjacent the rear end thereof is a leaf spring 49, having its free end operative against and closely overlying 15 the rearmost portion 51 of the plate 39. Fixed to the spring to extend inwardly therefrom to normally bear against the plate portion 51 is a detent pin 52, such pin being so disposed that it will engage in a slot provided 20 in the plate portion 51 when the latter is in retracted position, a slot 42 being here shown utilized for the purpose. In this manner, when the plate 39 is retracted, the pin 52 will engage in the slot 42 of the plate portion 51 25 and so prevent the return movement of the plate 39 when the latch bolt returns to its operative position. The spring 49 is here shown also arranged in contactual relation to the forward end of the spindle 31, such 30 spindle end being provided with an annular and axially extending cam edge 53 arranged to cooperate with the spring end to displace the same outwardly of the plate 39 to free the pin from slot 42 when the spindle is rotated to withdraw the latch plate. In this 35 manner, release of the plate 39 from its operative disposition to close slot 38 is arranged to occur only when an exit opening of the lock is effected.

40 A casing 54 for the structure now described is provided, said casing being here shown of one-piece structure and having side and front plate portions 56 and 57 respectively which cooperate with the back plate 11 to provide 45 a complete closure for the lock mechanism. An opening 58 is provided in the casing front 57 opposite the slot 38 to permit the insertion of a coin in the lock when said slot is open, while the latch bolt is arranged 50 to be reciprocated through a side perforation 59 having guard flanges 61 disposed therearound. Means are preferably provided for indicating the operative condition of the lock, and as here shown, such means comprises 55 the display of appropriate symbols 62 at the front of the lock in accordance with the position of plate 39. Preferably, and as here shown, the opening 58 is made wide enough to display one of said symbols and at the same 60 time control access to slot 38—in this manner the one opening serves two purposes. The symbols 62, it will be noted, are provided on the plate 39 forwardly of the edge 44 and extend parallel to said edge, such symbols 65 being so disposed that the one indicating an

operative condition of the lock will be disclosed in the opening 58 beside the slot 38 when the latter is uncovered, while the one indicating an inoperative condition of the lock will be displayed in the opening 58 when 70 the plate 39 is retracted to close the slot 38. In this manner, the insertion of a coin in the lock when the latter already contains a coin is positively prevented and the condition of the lock is at the same time positively indicated. 75

As here shown, the casing 54 is provided with a door opening 63 in the front 57 thereof for the reception of a door 64 and is arranged to be secured to the plate 11 partly by means of screw bolts 65 whose heads are exposed only when the door is open, and partly by means of a locking means 66 provided for the door. In the present embodiment, the door opening provides an inwardly offset 80 seat 67 in which the door is arranged to be disposed in flush relation with the wall 57. Upper portions of the seat are broken away to permit backwardly offset extensions 68 provided on the top door edge to be inserted 85 behind the wall 57 when the door is disposed in the opening. The door is arranged to be locked to its seat by means of a key operated and controlled lock 69 having the bolt end 71 thereof operatively engageable through and 90 behind a forwardly offset portion 72 of the plate 11. The bolt end 71 is provided with radially opposed extensions 73 arranged, when operative, to be engaged behind the wall portion 72, such wall being so perforated 95 as to permit the removal of the bolt when it is inoperative. Since a quarter turn only is involved as between the locked and unlocked positions of the bolt, a stop 70 is preferably provided on the lock mechanism housing, which stop is arranged to cooperate with stops 76 and 77 provided on the bolt to limit the bolt rotation to a quarter turn. In this manner, the door is locked to the back plate 11, thus providing a locking means for the 100 door which also assists in securing the casing sections together. 105

As here shown, the spindle 13 is operable by means of a knob 81 fixed thereto at the front of the door, while the spindle 31 is 110 arranged to be operated from the inside of the door by a suitable knob (not shown) so that dropping of the coin and the clearing of slot 38 is thus insured upon the opening of the door to effect an exit. If desired, the 115 operation of the spindle 31 may also be effected from the outside of the door by the use of a suitable key, the casing being here shown provided with a suitable keyway 83 for the purpose. Undue backward movement of the arm 16 is prevented by providing the member 14 with a second arm 84 which is arranged to engage a post 86 when the arm 16 lies at its desired backward position. 120

125 If desired, insertion of a coin through the 130

top of the casing may be provided for as is disclosed in the embodiment of Figure 5. As here shown, the casing top wall 91 is provided with a coin receiving slot 92 of appropriate size and members 93 are fixed on the plate 11 to provide a guideway from the slot 92 to the latch plate 8. The plate 17' which carries the movable plate 39' is, of course, in this case not slotted behind the opening 10 58' of the front plate 57', which opening is preferably only wide enough to display the appropriate symbol 62'. Preferably, the plate 39' is continued to the top wall 91 and is provided with an extension 94 disposed 15 beneath and adjacent such wall and arranged, when the plate 39' is retracted, to close the slot 92. In this manner, insertion of a second coin in the lock is prevented following an opening operation thereof by the aid of a 20 previously deposited coin, and before an exit operation of the lock is effected.

I claim:

1. In a door lock mechanism, a movable latch-plate having a slot therein arranged to 25 receive a coin, means arranged to releasably support said coin in said slot and operative thereagainst to effect a retractive displacement of said latch-plate, means normally inoperatively disposed for preventing the insertion of a second coin in said mechanism while said first coin is operatively disposed therein and arranged to be operatively disposed by and upon the retractive displacement of said latch-plate, detent means operative 30 to secure said last means in operative position, means for releasing said detent means, means operative independently of said first means for releasing said coin from said slot, and means effecting a return of said 35 second means to its normal inoperative position.

2. In a door lock mechanism, a movable latch-plate having a slot therein arranged to receive a coin, means operative to support 45 the coin in its slot and to act through the coin in said slot to retract the bolt, a casing providing an opening for the insertion of said coin into said slot, a normally inoperative closure for said opening arranged to move in the direction of movement of and alongside the latch plate, means on said latch-plate for operating said closure for completely closing said opening upon a displacement of said latch-plate, detent means for holding 50 the closure in operative position and means operative independently of said first means for effecting a return of said closure means to its inoperative position.

In testimony whereof, I have hereunto set 60 my hand at Oakland, California, this 20th day of April, 1927.

ALPHONSE GABRIEL.
